BORING TYPE MINING HEAD HAVING WEDGE MEANS

Clarence H. Brown, Chicago, Ill., assignor to Goodman Manufacturing Company, Chicago, Ill., a corporation of Illinois

Application May 10, 1954, Serial No. 428,669

3 Claims. (Cl. 262—7)

This invention relates to mining machines of the boring type and in particular to an improvement in the disposition of the boring arm assembly by reason of a specific arrangement thereof to provide improved clearance to wedge off the cores of the material being mined.

In mining machines of the boring type there is usually disposed at least two boring heads, each having a plurality of arms with forwardly projecting cutter bits and arranged with their arms in side-by-side overlapping relation to cut two contiguous bores. Also mining machines of this general type are usually further provided with horizontally disposed cutter chains or other auxiliary cutting devices at the floor and roof to smooth off the triangular cores left between the adjacent boring head so that the resulting bore is generally oval in cross-section.

In mining machines of the general type as described above it is customary to provide each of the boring head assemblies with a center bit and a plurality of radially extending boring arms carrying cutter bit supports having cutter bits thereon.

The resulting cut of each boring head assembly is a plurality of circular kerfs concentric to a center bore cut by the center bit. However, the radial thickness of each kerf is substantially smaller than the radial thickness of the core of the material being cut which has been left between the kerfs and much difficulty is had in providing clearance for this core material left by the cut to be wedged off and freed from the face.

It has long been a problem in the mining industry that when the cutter support on the boring arms have been disposed in a radial line that there is no clearance for the core of the mined material to be wedged free from the material's face. When these cutter bit supports are disposed in a radial line the mined material is crushed and a great percentage of fines is recovered rather than chunks or lumps. Accordingly, it has been found that by the specific arrangement and disposition of the cutter bit supports carrying the cutter bits thereon as laterally offset to the radial axis of the cutter arm and laterally offset to each other will provide sufficient clearance by reason of the radially outer kerf being formed circumferentially ahead of the core which is formed by the next radially inwardly adjacent kerf and the core between these kerfs will be wedged into the radially outward kerf.

It is therefore a primary object of this invention to provide a clearance for the material being mined so that the core material may be wedged-off from the main body thereof providing for more efficient and economical operation of the mining machine.

Other objects and advantages will appear from time to time as the following description proceeds.

The invention may best be understood by reference to the accompanying drawings, in which:

Fig. 1 is an elevational view of the head of the mining machine showing the invention in association with the other elements thereof;

Fig. 2 is a section along lines 2—2 of Fig. 1 and show-

2

ing the offset relation of the cutter bit supports on a boring arm assembly;

Fig. 3 is a section along line 3—3 of Fig. 1 showing the wedging of a core by a cutter bit support into the 5 radially outwardly adjacent kerf.

Referring to the details of the embodiment of my invention illustrated in the drawings, there is shown in Fig. 1 a mining machine indicated generally at 10 having two boring heads 12 arranged in side-by-side relation 10 with each other with the boring arms 14 rotating in overlapping non-interfering relation thereon.

It will be understood that the boring heads may have only two boring arms arranged diametrically from each other. It is to be noted that the boring arms 14 are 15 carried on the mining machine 10 at equally spaced angles from each other. Further, there is provided radially inwardly on each boring arm 14 a forwardly projecting cutter bit support 16, each cutter bit support carrying a plurality of cutter bits 18 along the outer ends thereof in the usual and accepted manner for cutting a circular kerf in the face of the material being mined. Further the outermost end of each arm 14 is provided with a forwardly projecting cutter bit support 20, similar to the support 16, and carrying thereon cutter bits 22 for cutting the outer kerf. Also, intermediate the supports 16 and 20 there is provided a cutter bits support 24 which projects forwardly and is similar to the supports 16 and 20. Intermediate support 24 carries thereon cutter bits 26 for cutting the intermediate kerf in the material being 30 mined. There may also be provided scoop plates 28 mounted on the end of each arm 14. A center bit 30, tapered near its inner end, projects from the front end of each boring head at the hub of the arms 14, and since the cutter bit supports, scoop plates and the center bit 35 are all well known in the art they need not be more fully described and form no part of the present invention.

For the purpose of brevity only a single boring arm 14 will serve as illustrating my invention, and accordingly further reference shall be made to such single arm. Referring now to the subject matter of my invention, namely a means for providing an improved clearance to wedge off the cores of the material being mined, attention is directed to Fig. 2, wherein it will be noted that the outermost cutter bit support 20 is circumferentially or laterally offset in the direction of rotation of the boring head 40 forward from the intermediate cutter bit support 24 and the inner cutter support 16. Further, the intermediate cutter bit support 24 is circumferentially or laterally offset in the direction of rotation of the boring head 12 45 forward of the innermost bit support 16 and rearward of the outermost bit support 20. Further, the innermost cutter bit support 16 is circumferentially or laterally offset in the direction of rotation of the boring head 12 rearward of both the intermediate support 24 and outer support 20. In addition, you will note that the innermost cutter bit support 16 is disposed in the direction of movement 50 of the mining machine forward of both the intermediate cutter bit support 24 and outer cutter bit support 20. Further, the intermediate support 24 is disposed in the direction of movement of the mining machine rearward of the inner support 16 and forward of the outer support 20. Also, the outer support 20 is disposed in relation to the movement of the mining machine rearward of both the inner support 16 and intermediate support 24.

This specific disposition of the cutter bit supports 16, 20 and 24 provides a clearance which is in fact the kerfs cut by the cutter bits 18, 22 and 26.

Attention is now directed to Fig. 3 wherein there is 55 shown a kerf 32 of the outermost cutter support 20 and it is readily seen that the core 34 of the material being mined is wedged radially outwardly by the specific wedge

configuration 36 of the intermediate support 24, and this mined material 34 has a clearance or opening into which it may be wedged and severed from its face. The cross-sectional wedge configuration of the innermost support 16 is similar to that shown in Figure 3 of the wedge configuration 36 of the intermediate cutter bit support 24, but by reason of the specific cross-sectional view of Fig. 3 the innermost kerf has not been cut and accordingly, it is not shown.

It is to be readily understood that by the specific disposition of these cutter bit supports 16, 20 and 24, which in turn carry thereon the cutter bits 18, 22 and 26 respectively provide for an improved clearance wherein the cores cut intermediate each kerf may be wedged into the radially outer kerf and thus easily severed from the mined material's face.

Although I have shown and described certain embodiments of my invention, it will be understood that I do not wish to be limited to the exact construction shown and described, but that various changes and modifications may be made without departing from the spirit and scope of the invention as defined in the appended claims.

I claim:

1. In a mining machine of the boring type having a radially extending rotating boring arm carrying a plurality of cutter bit supports thereon, said supports being circumferentially offset on said arm with each radially adjacent pair of said supports being disposed with the radial outer support thereof offset in the direction of rotation of said arm forward of the next adjacent radial inner support, each radial inner support having a wedge portion disposed in the direction of rotation of said arm rearwardly of each radial outer support, whereby a kerf will be cut by each outer support circumferentially forward of a kerf cut by each radial inner support providing

6
a clearance for a core of material intermediate the kerfs to be wedged radially outwardly into the radial outer kerf by each radial inner support during the operation of the machine.

5. 2. The structure defined in claim 1, wherein said wedge portion is defined by each inner support being tapered from a maximum radial thickness on the circumferential rearward portion to a minimum radial thickness on the circumferential leading portion and from a maximum radial thickness on the axial rearward portion to a minimum radial thickness on the axial forward portion.

3. In a mining machine of the boring type having a radially extending rotating boring arm carrying a plurality of cutter bit supports thereon, said supports being circumferentially offset on said arm with each radially adjacent pair of said supports being disposed with the radial outer support thereof offset in the direction of rotation of said arm forward of the next adjacent radial inner support, each radial inner support being tapered from a maximum radial thickness on the circumferential rearward portion to a minimum radial thickness on the circumferential leading portion and from a maximum radial thickness on the axial rearward portion to a minimum radial thickness on the axial forward portion defining a wedge portion offset in the direction of rotation of said arm circumferentially rearwardly of each radial outer support.
